STAPLE PULLER

James A. Hall, 401 S. 15th St., and Gustaf L. Sheberg,
1352 Keoncrest, both of San Jose, Calif.
Filed Dec. 7, 1962, Ser. No. 243,025
8 Claims. (Cl. 254—28)

The present invention relates to a staple puller, and pertains more particularly to a staple puller having a presser foot to restrain the paper or other material in which a staple is embedded, and a tongue to withdraw the staple.

In the past, staple pullers have been devised having a presser foot and a staple pulling tongue, such as, for example, the two De Generes Patents No. 2,215,662 and No. 2,481,647, and Misson Patent No. 2,762,604.

The present invention is an improvement in this general type of staple puller, and employs a single strip of spring sheet metal for both presser foot and staple pulling tongue, which spring strip also forms a body portion of the puller, with actuating means interposed between upper and lower portions of the spring strip to perform the staple pulling operation.

An object of the present invention is to provide an improved staple puller.

Another object of the invention is to provide a staple puller formed from a single strip of spring metal, with one end of the strip formed to provide a presser foot, and the other end thereof formed to provide a staple pulling tongue shaped to receive the presser foot flush therein.

A further object of the invention is to provide a staple puller comprising a strip of springy metal formed into a closed loop with end portions thereof interfitting, power multiplying actuating means being provided between superposed portions of the bent strip to forcibly separate the interfitting end portions thereof to withdraw a staple into which the end portions are inserted.

These, and other objects and advantages of the invention, will be apparent from the following description and the accompanying drawings, wherein:

FIG. 1 is a perspective view of a staple puller embodying the present invention, portions being broken away.

FIG. 2 is a front end elevational view of the staple puller of FIG. 1, with the staple pulling tongue and presser foot inserted into a staple to be pulled.

FIG. 3 is a view similar to FIG. 2, but with the cam levers tilted inwardly to withdraw the staple.

FIG. 4 is an exploded view of the two cam levers as they appear when disengaged and separated laterally from each other.

FIG. 5 is a sectional view taken along line 5—5 of FIG. 6.

FIG. 6 is a top plan view of the staple puller of FIGS. 1—5.

FIG. 7 is a top plan view of the sheet metal blank from which the body portion of the staple puller of FIGS. 1—6 is formed, a medial portion thereof being broken away, lines of bend being indicated in dash-dot lines.

FIG. 8 is an edge view of the body blank of FIG. 7.

Briefly, a staple puller A embodying the present invention comprises a body portion 10 formed of a strip of suitable spring metal. A staple pulling tongue 11, having an opening 12 therein, is formed on one end of the body 10, and is of a size to receive freely therein a presser foot 13 formed on the other end thereof. The body 10 has a rounded grip portion 14, and upper and lower parallel, superposed, spaced portions 17 and 18.

Actuating means comprising opposed levers 19 and 20 are fitted between the spaced, parallel body portions 17 and 18, and the spring body 10 is formed to normally bias the levers 19 and 20 toward their position shown in FIGS.

2

1, 2, 5 and 6, with the presser foot 13 interposed flush within the opening 12 in the tongue 11.

When the tongue 11, with the presser foot 13 fitted flush therein, are inserted beneath a staple B as shown in FIGS. 2 and 5, and the levers 19 and 20 are tilted inwardly toward each other as shown in FIG. 3, the staple B is withdrawn. An overlying, staple restraining tongue 21 is provided to catch any forcibly withdrawn staple and thus to retain it on the tongue 11.

10 Referring to the drawings in greater detail, the illustrative staple puller A comprises the spring strip body portion 10, which may be formed from a flat blank 10a (FIGS. 7 and 8) of spring metal, preferably a good grade of spring steel. In the present description corresponding parts of the body 10 and the blank 10a from which it is formed are designated by the same reference numerals. The pointed, staple pulling tongue is formed on one end of the blank 10a of a size to enter between the legs 22 (FIGS. 2 and 3) of a staple B to be pulled.

20 The pointed end of the tongue 11 is also sharpened to a dull edge, as best shown in FIG. 5, so that it may be easily forced beneath the transverse head portion 23 of a staple to be pulled. The opening 12 is provided in the staple pulling tongue 11, and extends back into the blank 10a beyond the tongue 11. The small, rectangular, staple restraining tongue 21 is also formed integrally within the inner end of the opening 12, while a pair of small positioning tabs 24 and 25 are formed integrally with the blank 10a, one at each side of the base of the staple pulling tongue 11.

30 The other end of the blank 10a has the presser foot 13 formed integrally thereon. This presser foot 13 is of a size and shape to fit freely into the opening 12 in the staple pulling tongue when the blank 10a is bent, as shown in FIGS. 1—3, 5 and 6, to form the body 10.

The blank 10a is bent to a circular curved to form the rounded grip portion 14, as best shown in FIG. 5. This rounded grip portion 14 is of a size to receive an annular hand grip member 27, which is inserted in closely fitted relation therein. The grip member 27 may be of molded plastic material, and the central opening therein preferably is of a size to receive the middle or third finger of an average user, although the size of this hole is not material to the invention.

40 45 A radially extending, annular ridge 28 (FIG. 1) is provided around each end of the annular insert 27, these ridges being axially spaced apart to receive the circularly curved hand grip portion 14 snugly therebetween to prevent displacement of the insert.

50 55 From the under side of the circularly curved hand grip portion 14, the portion of the body 10 having the presser foot 13 thereon extends at 18 (best shown in FIG. 5) flat, and tangential to the curved portion 14. From a point on the circle of curvature of the curved hand grip portion 14 spaced upwardly from the flat, tangential portion 17 by a distance sufficient to receive the cam levers 19 and 20 snugly therebetween, the body 10 is bent at 29 (note also FIG. 7) so that the portion 18 thereof (FIGS. 1, 2 and 5) extends flat, and parallel to the tangential bottom portion 17.

60 65 At 30 the body 10 is bent first downwardly, and then again forwardly at 31, while the small positioning tabs 24 and 25 are bent rearwardly as best shown in FIGS. 1 and 5 to overlie the bottom, tangential strip portion 18 just inwardly of the staple pulling tongue 11. The bends in the body 10 are so located, that in the normal position of the spring strip body 10, the presser foot 13 will be positioned flush within the opening 12 in the staple pulling tongue 11, and with slight marginal clearance therein as shown in FIG. 6.

70 It is important that the ends of the body strip 10, including the staple pulling tongue 11 and the presser

foot 13, be heat treated after punching, and preferably after forming, so that these portions will be strong and stiff, since they are sometimes stressed heavily in withdrawing a reluctant staple. Any relative bending of these parts prevents the presser foot from seating flush in the opening 12 in the staple pulling tongue 11, and thereby makes it difficult to insert them beneath a tightly driven staple.

To retain the levers 19 and 20 against displacement, a pair of rectangular openings 32 and 33 are provided in the flat, upper portion 17 of the body 10 to receive a pair of lever positioning prongs 34 and 35, one of which is provided on each of the levers 19 and 20. As illustrated, the two levers 19 and 20 are identical, so that they can be made from a single mold. The levers preferably are of suitable, molded plastic material, and since a large number of suitable plastics for this purpose are well known to those familiar with the plastics industry, it will be unnecessary to enumerate them herein. Since the levers 19 and 20 are identical, only the one 19 will be described in detail.

The lever 19 is in general of block L shape in side elevation, the upwardly extending leg 37 thereof comprising a lever for gripping between the thumb 38 and forefinger 39 of a user's hand, as shown in FIG. 3, for withdrawing a staple B. An outwardly projecting rib 40 is provided across the upper end of each lever leg 37 to prevent the user's hand from slipping off when the cam levers are tilted inwardly in operating the device as shown in FIG. 3.

The base leg 41 of the lever 19 has the upper and lower faces thereof parallel, and spaced apart to fit snugly between the flat, parallel body portions 17 and 18 of the body 10. The upwardly projecting, curved prong 34 is formed integrally on the upper surface of the base portion 41, and is located for insertion into one of the openings 32 or 33 when the edge of the upper, flat body portion 17 is in the angle between the base 41 and upward leg 37 of the lever upon which the prong is provided. The prong 34 is curved, with its axis of curvature at the angle between the base and upward legs of its cam lever, so that when the levers are tilted inwardly from their positions of FIG. 2 to that of FIG. 3, the tongues will withdraw smoothly through their respective openings.

The base leg 41 of the lever 19 is notched out at 42 and 43 to provide two fingers 44 and 45. The notches 42 and 43 are wider at their bases, and narrower at their outer ends, while the fingers 44 and 45 are wider at their outer ends, and narrower at their base ends. The finger 44 on one side of each base portion is of substantially the same shape as, but slightly narrower than, the notch 42 on the other side thereof, while the finger 45 is of substantially the same shape as, but slightly narrower than, the notch 43 between the fingers 44 and 45.

The inner end face 47 (FIGS. 2 and 3) of each notch 42 and 43 slopes inwardly and downwardly, while the outer end face 48 of each finger 44 and 45 slopes outwardly and downwardly at the same angle. Thus, when two of the identical levers 19 and 20 are reversed, the fingers 44 and 45 of one thereof can be inserted from below into the notches 42 and 43 of the other, and the fingers of the two levers will then be interdigitated with the cam levers opposite each other as best shown in FIG. 6. The fingers 44 and 45 are sufficiently narrower than their respective notches as to fit and work freely therein without binding.

The outwardly sloping end faces 48 on the fingers 44 and 45 will engage the similarly sloping end faces 47 of the notches in which they are inserted to prevent the levers 19 and 20 from being tilted outwardly away from each other. A short bevel 49 is formed on the under side of each finger 44 and 45 at its outer end

5 to shorten the effective length of the fingers and thereby increase the mechanical advantage of the levers.

In using the illustrative staple puller A, the levers 19 and 20 are grasped lightly between the thumb 38 and index finger 39, and if desired the middle or third finger of the same hand may be inserted in an obvious manner in the annular grip member 27, although this latter is not necessary, and is not illustrated in FIG. 3. The staple pulling tongue 11, with the presser foot 13 flush therein, is then forced beneath the transverse head portion 23 of a staple B to be removed, care being exercised not to squeeze the levers inwardly toward each other until the tongue 11 is fully inserted into the staple. The levers 19 and 20 are then squeezed together, tilting them toward each other as shown in FIG. 3 until the staple is fully withdrawn. Frequently the staples will snap sharply upwardly as they are withdrawn, in which case they strike the overlying, restraining tongue 21, which arrests their upward flight and drops them back onto the tongue 11, from which they gravitate when the staple puller A is tilted forwardly.

The invention provides a simple, strong, easily operated staple puller, wherein its one piece body facilitates accurate, inexpensive manufacture, which can be done with small punching and bending dies, and wherein the plastic grip member 27 and actuating members 19 and 20 are simple plastic moldings, which can be easily and quickly assembled with the body.

While we have illustrated and described a preferred embodiment of the present invention, it will be understood, however, that various changes and modifications may be made in the details thereof without departing from the scope of the invention as set forth in the appended claims.

Having thus described the invention, what we claim as new and desire to protect by Letters Patent is defined in the following claims.

We claim:

1. A staple puller comprising:
  - (a) a pair of strips of spring metal mounted in parallel, spaced, superposed relation,
  - (b) a presser foot projecting from one end of the lower strip,
  - (c) a staple pulling tongue projecting from the end of the upper strip, and having an opening therein of a size to receive the presser foot therein,
  - (d) a handle grip portion interconnecting the rear portions of said parallel spring strips and lying wholly above the lower one of said strips,
  - (e) and a pair of actuating levers interposed from opposite sides between the superposed portions of the strips and tiltable toward each other to forcibly urge the tongue upwardly relative to the presser foot, thereby to exert a pulling force on a staple into which the tongue, with the presser foot flush therein, has been inserted.

2. A staple puller comprising:
  - (a) a body portion formed of a single strip of spring metal,
  - (b) a presser foot projecting from one end of the body strip,
  - (c) a staple pulling tongue projecting from the other end of the strip, and having an opening therein of a size to receive the presser foot therein,
  - (d) a curved portion formed by bending the strip reversely upon itself to position a portion of the strip inwardly from the tongue in upwardly spaced, superposed relation to a portion of the strip inwardly from the presser foot,
  - (e) a pair of bends in the strip, one adjacent the base of the tongue and the other in inwardly spaced relation lengthwise of the strip to normally position the presser foot flush within the opening in the tongue,
  - (f) and a pair of actuating levers interposed from opposite sides between the superposed portions of the

strip and tilttable toward each other to forcibly urge the tongue upwardly relatively to the presser foot, thereby to exert a pulling force on a staple into which the tongue, with the presser foot flush therein, has been inserted.

3. A staple puller comprising:

- (a) a body portion formed of a single strip of spring metal,
- (b) a presser foot projecting from one end of the body strip,
- (c) a staple pulling tongue projecting from the other end of the strip, and having an opening therein of a size to receive the presser foot therein,
- (d) a curved portion formed by bending the strip reversely upon itself to position a portion of the strip inwardly from the tongue in upwardly spaced, superposed relation to a portion of the strip inwardly from the presser foot,
- (e) a pair of bends in the strip, one adjacent the base of the tongue, and the other in inwardly spaced relation thereto lengthwise of the strip to normally position the presser foot flush within the opening in the tongue,
- (f) a pair of L-shaped levers with one leg of each thereof interposed from opposite sides between the superposed portions of the strip,
- (g) the other legs of said levers extending upwardly for grasping between the thumb and forefinger of a user for tilting the levers toward each other to forcibly urge the tongue upwardly relative to the presser foot,

thereby to exert a pulling force on a staple into which the tongue, with the presser foot flush therein, has been inserted.

4. An arrangement according to claim 3 wherein a plurality of alternate notches and endwise projecting fingers are provided on the ends of the lever legs inserted between the superposed portions of the body, the fingers of one

leg fitting into the notches of the other in interdigitated relation.

5. An arrangement according to claim 4 wherein the notches are wider at their bases, and the fingers are wider at their free ends for interlocking relation against endwise separation when in interdigitated relation between the superposed portion of the body.

6. An arrangement according to claim 5 wherein the fingers on one lever leg correspond substantially to the notches on the other, and are sufficiently narrower to be freely insertable, and relatively tilttable when in interdigitated relation between the superposed portions of the body.

7. An arrangement according to claim 4 wherein the base ends of the notches are offset inwardly and downwardly, and the outer ends of the fingers are offset outwardly and downwardly to prevent relative outward tilting of the levers when in interdigitated relation between the superposed portions of the body.

8. An arrangement according to claim 4 wherein an upwardly extending prong is provided on the leg of each lever which is interposed between the superposed portions of the body, and a pair of openings is provided in the uppermost of the superposed portions of the body to receive these prongs when the lever legs are interposed between the superposed body portions, thereby to prevent displacement of the levers relative to the body.
